DESIGN FOR A TRAILER VEHICLE BODY

Edward Mullen, Leo H. Garman, and James C. Jordan, Detroit, Mich., assignors to Mechanical Handling Systems, Inc., Detroit, Mich., a corporation of Michigan

Application January 31, 1946, Serial No. 126,134

Term of patent 14 years

(Cl. D14—3)

To all whom it may concern:

Be it known that we, Edward Mullen, Leo H. Garman, and James C. Jordan, citizens of the United States, residing at Detroit, in the county of Wayne and State of Michigan, have invented a new, original, and ornamental Design for a Trailer Vehicle Body, of which the following is a specification, reference being had to the accompanying drawings, forming part thereof. These accompanying drawings consist of Fig. 1, a side elevational view of a vehicle body embodying this new design; Fig. 2, a front quarter perspective view; and Fig. 3, a perspective view taken from the rear quarter and above.

The characteristic features of our design reside in the portions shown by means of full lines in the drawings.

We claim:

The ornamental design for a trailer vehicle body, as shown and described.

EDWARD MULLEN.
LEO H. GARMAN.
